METHOD OF REDUCING PLUTONIUM WITH
FERROUS IONS

John Leonard Dreher, El Cerrito, Calif., Daniel E. Kosland, Chicago, Ill., Stanley G. Thompson, Richmond, Calif., and John E. Willard, Madison, Wis., assignors to the United States of America as represented by the United States Atomic Energy Commission

No Drawing. Application December 2, 1947
Serial No. 789,332

11 Claims. (Cl. 23—14.5)

This invention relates to the separation of plutonium from elements commonly found with it, and more particularly is concerned with an improvement in the oxidation-reduction method of separating plutonium from other elements.

Plutonium is the element with atomic number 94. Reference herein to plutonium or to other elements is to be understood as denoting the element generically whether in its free state or in the form of a compound, unless otherwise indicated by the context.

Plutonium is ordinarily obtained by irradiating uranium with neutrons. It is well known that the plutonium thus obtained is a small part of the irradiated uranium mass and that other constituents of the mass include, as radioactive fission products, elements of the group having atomic numbers between 32 and 63. Many of these radioactive fission products have great value as tracers in various fields of research particularly in the physical, medical, and chemical fields and it is therefore highly desirable that the plutonium be separated from these fission products and from the uranium with which it is associated.

The most successful method of separating plutonium from the other constituents of an irradiated uranium mass is the oxidation-reduction method which depends upon the fact that plutonium exists in more than one state of oxidation and that compounds formed by plutonium in these various oxidation states differ widely in their solubility characteristics.

The most important of the oxidation-reduction separation processes is the bismuth phosphate-lanthanum fluoride process. This process may be arbitrarily divided into four sequences of operations or steps. These are usually referred to as the extraction, decontamination, concentration and isolation steps. Many of the operations in these steps are cyclic in nature and these operations may be repeated as often as necessary to achieve the desired effect. In the description which follows, a precipitate containing plutonium will be referred to as a "product precipitate," and a precipitate which carries other elements from a solution containing plutonium in a valence state in which it is not carried with the particular precipitate, is referred to as a "by-product precipitate."

In the extraction step of the bismuth phosphate-lanthanum fluoride process the neutron-reacted uranium is aged from thirty to ninety days to permit the neptunium present in the uranium to decay to plutonium. The uranium mass is then dissolved in nitric acid to form a uranyl nitrate solution containing all of the uranium as well as the plutonium and fission products. Dissolution of the uranium mass in the hot nitric acid causes some oxidation of the plutonium present to its highest oxidation state, the +6 state, in which state plutonium forms a soluble phosphate. The solution is therefore contacted with a reducing agent and the plutonium converted to the tetravalent state, in which state it forms an insoluble phosphate. A plutonium carrier precipitate of

2

bismuth phosphate is then formed in the uranyl nitrate solution and separated from the solution carrying with it the tetravalent plutonium and certain of the fission products, which form insoluble phosphates, particularly zirconium and columbium, leaving the uranium and bulk of the fission products in solution. This separation of the product precipitate completes the extraction step.

The operations which follow the extraction step are designed to separate the plutonium from the radioactive fission products which are carried with it in the first plutonium precipitation and are usually referred to as the decontamination step. In this step the bismuth phosphate-plutonium carrier precipitate obtained in the extraction step is dissolved in nitric acid and the plutonium is oxidized to the hexavalent state. A bismuth phosphate precipitate is then formed in and separated from the solution containing the plutonium and fission products. The phosphate-soluble hexavalent plutonium remains in solution during this "by-product" precipitation but the phosphate-insoluble fission products are carried with the bismuth phosphate precipitate. The plutonium is then reduced to the tetravalent state and separated from the solution by forming a bismuth phosphate carrier precipitate in the solution and separating it therefrom. This operation completes the decontamination step but this step may be repeated as many times as necessary in order to secure the decontamination desired.

The bismuth phosphate product precipitate obtained in the last operation of the decontamination step contains a very small proportion of plutonium to bismuth phosphate and it is desirable that the ratio of plutonium to carrier be increased. This is accomplished by the concentration step which follows. In this step the bismuth phosphate product precipitate is dissolved in nitric acid and the plutonium is oxidized to the hexavalent state. The bismuth phosphate present in the solution is then substantially removed by precipitation and the plutonium is converted to the tetravalent state. A lanthanum fluoride-plutonium carrier precipitate is formed in, and separated from, the solution. The lanthanum fluoride-plutonium carrier precipitate is dissolved in nitric acid and metathesized with an alkali metal carbonate or hydroxide to form a mixed plutonium and lanthanum hydroxide. This mixed hydroxide is separated from the solution and may be dissolved in a much smaller quantity of a nitric acid solution, thus effecting concentration of the plutonium to a degree that permits of its direct precipitation from the solution. This operation completes the concentration step and prepares the plutonium for the isolation step which follows.

The lanthanum hydroxide-plutonium hydroxide precipitate after being dissolved in nitric acid is treated with a reducing agent to reduce any plutonium which may have been oxidized to the hexavalent state by the warm nitric acid. The tetravalent plutonium is then precipitated from solution as the peroxide to complete the isolation step and the separation process.

There are several alternate procedures involving the use of carriers other than bismuth phosphate and lanthanum fluoride and containing other minor variations in the above-described process. The oxidation-reduction process, in general, however, follows the outline above.

It will be noted that each step of the above-described bismuth phosphate-lanthanum fluoride plutonium separation process contains at least one plutonium reduction operation. In each of these operations the plutonium is converted in an acid medium from the hexavalent to the tetravalent state, in which state it is carried quantitatively by either bismuth phosphate or lanthanum fluoride. Because of the small percentage of plutonium involved in the process, it is essential that the utmost efficiency be maintained in these reduction operations and a great deal

of research has been done upon this problem. Numerous reducing agents have been used including SO_2 , N_2H_4 , NH_2OH , and U^{+4} . All of these have been found, however, to have certain disadvantages. For example, some of the agents reduce the plutonium too slowly or require such high temperatures in order for the reduction reaction to proceed that there is excessive corrosion of the process vessels by the acid solution. Other agents have such positive oxidation-reduction potentials that they reduce the plutonium to the trivalent state in which state it carries poorly with most carrier precipitates. It is often difficult to remove the excess reducing agent, and after reduction of plutonium to the trivalent state, this excess reducing agent tends to prevent the subsequent oxidation of the plutonium to the quadrivalent state. Other reducing agents introduce undesirable ions into the solution, such as the colloidal sulfur often produced when SO_2 is used.

It is an object of this invention to provide a method for reducing plutonium from a higher to a lower valence state.

It is an additional object of this invention to provide an improvement in the plutonium reduction steps of the bismuth phosphate-lanthanum fluoride plutonium separation process.

Added objects and advantages of the present invention will be evident from the following description.

In accordance with the present invention, it has been found that the ferrous ion is a most effective reducing agent for plutonium. The oxidation-reduction potential of the ferrous-ferric couple is sufficiently less negative than the potentials of the plutonium couples that ferrous ion will readily reduce plutonium from any higher to any lower valence state. The oxidation-reduction potentials of the various plutonium couples and of the ferrous-ferric couple are as follows:

The method of reducing either the hexavalent or tetravalent plutonium ion to the trivalent state comprises treating the oxidized plutonium ion contained in an aqueous acidic solution with ferrous ion.

The quantity of ferrous ion required to reduce plutonium may be readily calculated from the equations given above. It has been found desirable to use amounts of ferrous ion somewhat larger than stoichiometric proportions in order to increase the rate of reduction, unless the reduction is carried out in the presence of other ions which would give undesirable side results with excess ferrous or ferric ion.

Any soluble ferrous salt, such as the ferrous chloride, nitrate, or sulfate, is a suitable agent for introducing the ferrous ion into the solution. Ferrous ammonium sulfate has been found to be a very satisfactory reagent for this purpose. It is a crystalline salt readily soluble in water and can be dissolved to form an aqueous solution which is easily handled. The preferred $\text{Fe}(\text{NH}_4)_2(\text{SO}_4)_2 \cdot 6\text{H}_2\text{O}$ solution is a 20% solution containing 0.1% sulfuric acid; the sulfuric acid tends to stabilize the ferrous salt by preventing hydrolysis. The reduction reaction of plutonium ions with ferrous ion is carried out in an acid solution. The reason for this is that the hexavalent, tetravalent and trivalent plutonium ions all form insoluble hydroxides in basic solutions. There is also a strong tendency for the Pu^{+4} ion to disproportionate to the +3 and +6 states at low acid concentration. For these reasons the reduction is best carried out in a moderately acid solution, for example, 0.5 to 1.5 N HNO_3 .

The time and temperature which the reaction requires are quite dependent on each other. Thus, at temperatures from 50-90° C. the reduction takes place almost

instantaneously, however, at room temperature it may take a much longer time.

The Pu^{+6} ion is difficult to convert to the quadrivalent state directly, since the reduction potentials of the various plutonium couples are so close together that a reducing agent which will cause the reduction of hexavalent plutonium to quadrivalent plutonium will also normally cause the reduction of the hexavalent plutonium to the trivalent state. The conversion of hexavalent plutonium to the quadrivalent state may, however, be brought about by reducing the hexavalent plutonium to the trivalent state and then oxidizing the trivalent plutonium to the quadrivalent state.

We have discovered that where hexavalent plutonium is reduced with ferrous ion in a nitric acid solution, the excess ferrous ion may be oxidized to the ferric state and the trivalent plutonium ion may then be oxidized to the quadrivalent state by digesting the nitric acid solution containing the plutonium at an elevated temperature for a suitable time. The ferrous ion is first completely converted to the ferric state followed almost instantaneously by the conversion of the trivalent plutonium to the quadrivalent state. This conversion can often be observed by a color change which usually occurs in the nitric acid solution. A greenish-brown color indicates the presence of the ferrous ion and this color intensifies as the potential rises but disappears at the final conversion of the ferrous to the ferric state. It is presumably caused by a ferrous-nitroso complex. The time required for the conversion of the trivalent plutonium to the quadrivalent state is somewhat dependent upon the temperature of the reaction solution, and the acid concentration. Where the solution was made .04 M in ferrous ion, ferrous ion was completely oxidized by 0.5 N nitric acid in five minutes at 75° C. and by 0.3 N nitric acid in ten minutes at the same temperature. However, at 50° C. an 0.04 Fe^{+2} concentration required three hours in 0.3 N nitric acid, twenty-seven minutes in 0.5 N nitric acid, and less than five minutes in 1 N nitric acid for complete conversion to the ferric state.

The effect of the temperature of digestion upon the length of time required to convert the ferrous to the ferric ion, was shown by experiments in which it was found that ferrous ion may last as long as sixty-six minutes at 25° C. in a 1.0 N nitric acid solution. The solution conditions of the experiment simulated those of the solution containing hexavalent plutonium which is converted to the tetravalent state in the decontamination step of the bismuth phosphate-lanthanum fluoride plutonium separation process. At 50 to 75° C., the ferrous ion is completely oxidized to the ferric ion within five minutes under similar conditions. Since it has also been shown that trivalent plutonium is oxidized to the tetravalent state in the above-mentioned solution almost immediately following the oxidation of the last of the ferrous ion present, these time factors may be considered to apply to the time required to convert the trivalent to the tetravalent plutonium under these conditions.

An alternate method of converting hexavalent to quadrivalent plutonium depends upon the effect of quadrivalent-plutonium-complexing agents contained in the reaction solution. Certain ions, particularly fluoride, oxalate, and phosphate ions, strongly complex plutonium in the tetravalent state. The effect of the presence of a complexing agent on the oxidation-reduction potential may be shown by the following equation in which hydrochloric acid was substituted for nitric acid in order to prevent the slow drift of potential caused by nitric acid oxidation of trivalent plutonium.

In the fluoride solution ferrous ion will reduce hexavalent plutonium to the tetravalent state but ferrous ion will not reduce plutonium to the trivalent state. Moreover, the $\text{Pu}^{(IV)}/\text{Pu}^{(VI)}$ potential is shifted in the

direction of making Pu (VI) a more powerful oxidizing agent in the presence of the fluoride ion so that less ferrous ion is required to reduce Pu (VI) to Pu (IV) than would be required for the same reduction in the absence of fluoride ion.

In the bismuth phosphate-lanthanum fluoride process, which has been previously described, there is a plutonium reduction operation in each of the four steps: the extraction, decontamination, concentration, and isolation step. The plutonium in each case is converted from the hexavalent to the tetravalent state. Ferrous ion may be used in the process of this invention in the reduction operation in each of these steps and has proved to be particularly advantageous in the decontamination step. In this step plutonium is converted from the hexavalent to the tetravalent state following a by-product precipitation during which the plutonium is maintained in the hexavalent state in solution. After the bismuth phosphate by-product precipitation, the plutonium is reduced and precipitated from solution with a bismuth phosphate precipitate as the carrier. The solution which contains the hexavalent plutonium just prior to the reduction of plutonium usually contains about 1 N HNO₃, 0.6 N H₃PO₄, 0.1 N K₂Cr₂O₇, small quantities of bismuth ion and a very small concentration of radioactive fission products such as lanthanum, zirconium, and columbium. The K₂Cr₂O₇ present is a holding oxidant and its purpose is to maintain the plutonium in the hexavalent state during the bismuth phosphate by-product precipitation. Following the conversion of the hexavalent plutonium to the tetravalent state in this solution a bismuth phosphate product carrier precipitate is formed in the solution and separated therefrom, thus separating the plutonium from foreign cations contained in the solution which are not carried with bismuth phosphate.

The apparent disadvantages of the use of ferrous ion as a reducing agent in the decontamination cycle of the bismuth phosphate-lanthanum fluoride process, namely, that ferrous ion forms a strongly bound complex with the phosphate ion, and that ferrous ion reduces hexavalent plutonium to the trivalent state, are overcome by the process of this invention. The disadvantage of the formation of ferrous-phosphate complex ion is overcome by using only a small excess of ferrous ion over that required to reduce the hexavalent plutonium and any oxidizing agent present and by increasing the phosphate ion concentration in the solution to about 0.6 M H₃PO₄. The reduction of the plutonium to the difficultly carriable trivalent state is overcome as described above either by oxidizing the trivalent plutonium formed to the tetravalent state by digestion at moderately elevated temperature in nitric acid solution, or by reducing the plutonium in the presence of a complexing agent for quadrivalent plutonium.

There are characteristics of the ferrous ion which greatly increase the decontamination of plutonium in this stage. For example, ferrous and ferric ions tend to solubilize rare earth phosphates which are present in solution; thus lanthanum phosphate present in solution is carried by a bismuth phosphate precipitate to the extent of 30% in the absence of ferrous ion but of only 3% in its presence. This tends to prevent the rare earth fission products in solution from carrying with the product bismuth phosphate carrier precipitate following a ferrous reduction step.

The improvement in the decontamination cycle obtained when ferrous ion is used as a reducing agent by the process of this invention is shown by the following table in which the decontamination results obtained when ferrous ion is used are compared with those obtained with a uranous ion reducing agent and an oxalate reducing agent. It will be noted that the bismuth phosphate product precipitate carries at least twice as much of the radioactive fission products (which are β - and γ -emitters) after a uranous reduction and four times as much after

an oxalate reduction, as after the ferrous reduction. The conditions of the experiments shown in the examples were as follows: three aliquots of a solution containing 1 N HNO₃, 0.1 M H₃PO₄, 0.002 M K₂Cr₂O₇, a tracer quantity of hexavalent plutonium and tracer quantities of fission product elements were reduced with ferrous ion by the process of this invention, uranous ion and oxalate ion, respectively. A bismuth phosphate product precipitate was then formed in and separated from each of the three aliquots and the precipitate and supernatant solutions were then analyzed for plutonium and for fission products by radiometric analysis of alpha, beta, and gamma counts. The presence of plutonium is indicated by percentage of alpha counts, and the presence of fission products by the percentage of beta and gamma counts.

	BiPO ₄ product in decontamination cycle.....	71	24	18
0.005 M H ₂ C ₂ O ₄	Waste supernatant after product pptn.....	24	63	84

The preferred method of reducing hexavalent plutonium by the process of this invention in the decontamination cycle of the bismuth phosphate-lanthanum fluoride process is to introduce ferrous ion into the solution, preferably as a 20% ferrous ammonium sulfate solution, in a sufficient quantity to make the solution about 0.03 M in ferrous ion in excess of the holding oxidant present, then digesting the solution at 75° C. with agitation for one hour. The plutonium which is present in about 1×10^{-4} M concentration is almost immediately reduced to the trivalent state and the one-hour digestion at elevated temperature which follows completely oxidizes the excess ferrous ion to the ferric state and the trivalent plutonium to the tetravalent state. The tetravalent plutonium may then be removed from the solution by formation and separation of a bismuth phosphate carrier precipitate.

Variables which affect the reduction step include the ferrous concentration, temperature, order of addition, nitric acid concentration, and method of forming the subsequent bismuth phosphate carrier precipitate. Under normal conditions, a ferrous concentration of between 0.002 M and 0.05 M ferrous ion in excess of the holding oxidant present has been found to give entirely satisfactory reduction. At lower concentrations the iron may be oxidized by air and nitric acid before reducing all of the plutonium; at higher concentrations interference with bismuth phosphate carrying of tetravalent plutonium occurs.

The importance of the temperature variable is due to the necessity of oxidizing the trivalent plutonium to the tetravalent state in the process. The temperature and time required for this operation will vary with other conditions, as previously described. However, at 1 N nitric acid concentration and 75° C., we have found that a one-hour digestion period is ample to oxidize any excess ferrous ion to ferric ion and all trivalent plutonium to the tetravalent state. Under normal conditions, the temperature and time could be considerably reduced without adversely affecting the conversion of the plutonium

and subsequent carrying of the tetravalent plutonium by the bismuth phosphate precipitate.

The preferable manner of forming the bismuth-phosphate-tetravalent-plutonium carrier following the reduction step is the "direct strike" method, i.e., the bismuth ion is added to the solution prior to the addition of the phosphate ion. Should the "reverse strike," which is the addition of the phosphate ion prior to the addition of the bismuth ion, be used, however, it is desirable to use a smaller quantity of ferrous ion in the preceding reduction. Thus, tests have shown that a ferrous ion concentration of 0.03 M will cause consistent losses of 10% when a reverse strike is used. At a 0.01 M ferrous concentration, however, no losses will occur because of the ferrous concentration when the bismuth phosphate precipitate is formed by either method.

Now that the plutonium reduction has been described, its use in the decontamination cycle of the bismuth phosphate-lanthanum fluoride plutonium separation process may be illustrated by the following example.

Example

The steps of the bismuth phosphate-lanthanum fluoride process, as described above, have been carried out through the first by-product precipitation of the decontamination cycle. One and sixty-four/hundredths lb. of $\text{Pu}(\text{NO}_3)_6$ is contained in 20,400 lbs. of the solution. The components of the solution include 1680 lbs. of nitric acid, 183 lbs. of phosphoric acid, 8 lbs. of sodium dichromate, 1 lb. of ammonium nitrate, 4 lbs. of sodium nitrate, and 18522 lbs. of water. To this solution 1575 lbs. of 14% ammonium silicofluoride solution is added, and then 1950 lbs. of 20% $\text{FeSO}_4 \cdot (\text{NH}_4)_2\text{SO}_4 \cdot 6\text{H}_2\text{O}$ solution is added. The solution is heated to 75° C. and maintained at this temperature for one hour with constant agitation. Two hundred sixteen lbs. of an aqueous bismuth solution containing 24% BiONO_3 and 19% HNO_3 is then added to the solution at the rate of 3½ lbs. per minute and the solution is agitated for thirty minutes at 75° C. Nineteen hundred forty-five lbs. of a phosphoric acid solution containing 73.5% H_3PO_4 and 1.2% HNO_3 is added to the solution and the solution is agitated for two hours at 75° C. The solution is then cooled to 50° C. and the bismuth phosphate plutonium carrier precipitate is separated by centrifugation.

Another modification of the invention is concerned with the conversion of plutonium from the hexavalent to the tetravalent state, said plutonium being contained in a solution with a holding oxidant of dichromate ion present. It has been found that hydrogen peroxide will reduce dichromate ion, but not hexavalent plutonium, and this modification comprises treating the solution containing the hexavalent plutonium and dichromate ion, with a sufficient quantity of hydrogen peroxide to reduce the dichromate ion, and then introducing a sufficient amount of ferrous ion to reduce the hexavalent plutonium to the tetravalent state.

This modification has been found to be very useful in the conversion of hexavalent plutonium to the tetravalent state in the concentration cycle of the bismuth phosphate-lanthanum fluoride-plutonium separation process. In this cycle, the plutonium is converted to the tetravalent state and then separated from solution with a lanthanum fluoride carrier precipitate. The carrying of plutonium by lanthanum fluoride is inhibited with a smaller quantity of iron than is the case when tetravalent plutonium is carried with a bismuth phosphate precipitate. This modification is, therefore, particularly useful in this concentration cycle, since the conversion of the plutonium to the tetravalent state is effected with a much smaller quantity of ferrous ion than would be required if both the dichromate and the hexavalent plutonium were reduced by ferrous ion alone.

Another situation in which this modification has proved particularly useful, is where hexavalent plutonium is con-

verted to the tetravalent state with fluoride ion present in the reduction solution to complex the tetravalent plutonium formed and prevent its further reduction to the trivalent state. The presence of the fluoride ion would cause undesirable corrosion in the reaction vessels if the reaction solution were heated much above room temperature, but if the reaction is carried out at room temperature, either a larger amount of ferrous ion or a much longer time will be required to effect the reduction of the plutonium with ferrous ion alone for the reduction of the dichromate ion and the hexavalent plutonium. This modification is particularly desirable in this situation then, because the dichromate ion may be reduced at room temperature with hydrogen peroxide and a small quantity of ferrous ion will be sufficient to effect the reduction at room temperature of the hexavalent plutonium.

The hydrogen peroxide is added in an amount approximately equivalent to the dichromate ion contained in solution. Between 85 and 115% of the stoichiometrically equivalent amount has been found satisfactory. The dichromate is almost instantly reduced and a small amount of ferrous ion is then added to reduce any remaining peroxide and to reduce the plutonium. Where the plutonium is present in solution in approximately .0001 M concentration, an iron concentration of 0.015 to 0.20 M (22-33% of the amount equivalent to the initial dichromate concentration) has been found to give satisfactory results, where the solution is 1.0 N in HNO_3 and 1.0 N in HF. The optimum conditions for the reduction of plutonium where it is present in a solution in approximately 0.0001 M concentration, the solution also containing 1.0 N HNO_3 , 1N HF, and 0.1 N $\text{K}_2\text{Cr}_2\text{O}_7$, are: addition of H_2O_2 in amount sufficient to make the solution 0.075 M, agitation for one-half hour at room temperature, followed by the introduction of a sufficient quantity of ferrous ion to make the solution 0.02 M in ferrous ion, and agitation for an additional one-half hour at room temperature.

The H_2O_2 concentration may be decreased somewhat by increasing the Fe^{+2} concentration, but the H_2O_2 concentration should not be increased greatly over 0.075 M, since any excess would tend to oxidize the ferrous ion added later, thus preventing complete reduction of the plutonium.

Now that the results of the variation of factors in this modification have been discussed in general, the effect of variations may be illustrated by the following tables in which particular conditions are shown. These tables are given by way of illustration and not to limit the invention. Unless otherwise specified the conditions of the experiments below were as follows: 0.001 M Pu /liter, 1 N HF, 1 N HNO_3 , 0.1 N $\text{K}_2\text{Cr}_2\text{O}_7$. The solutions were prepared by oxidizing plutonium with 0.1 N $\text{K}_2\text{Cr}_2\text{O}_7$ in 1 N HNO_3 solution after which the solutions were made 1 N in HF. The hydrogen peroxide and ferrous ion were added according to the conditions listed below. Then a lanthanum nitrate salt was added to cause

the formation of a lanthanum fluoride precipitate, and this was digested for one-half hour before the precipitate was separated by centrifuging. The amount of reduced plutonium which was carried by the lanthanum fluoride precipitate was determined by radiometric analysis.

While there have been described certain embodiments of our invention, it is to be understood that it is capable of many modifications. For example, it may be used not only in all of the reduction steps of the bismuth phosphate process, but also in the reduction steps of many other oxidation-reduction plutonium separation processes. Changes, therefore, may be made without departing from the spirit and scope of the invention as described in the appended claims, in which it is the intention to claim all novelty and invention as broadly as possible in view of the prior art.

What is claimed is:

1. The method of reducing plutonium from the hexavalent to the tetravalent state, which comprises contacting said hexavalent plutonium contained in an aqueous acidic solution, with ferrous ion in the presence of a complexing agent for tetravalent plutonium selected from the group consisting of fluoride, oxalate and phosphate.

2. The method of reducing plutonium from the hexavalent to the tetravalent state, which comprises contacting said hexavalent plutonium contained in an aqueous nitric acid solution with ferrous ion in the presence of fluoride ion.

3. The method of converting hexavalent plutonium to the tetravalent state, which comprises treating said hexavalent plutonium contained in an aqueous nitric acid solution with an amount of ferrous ion sufficient to convert the plutonium to the trivalent state, then digesting the solution at a temperature between 25 and 100° C. until the ferrous ion is converted to the ferric state and

the trivalent plutonium converted to the tetravalent state.

4. The method of separating dissolved hexavalent plutonium from an aqueous nitric acid solution, which comprises treating said solution with an excess of ferrous ion over the amount required to reduce the hexavalent plutonium to the trivalent state, then digesting the solution at a temperature of from 25 to 100° C. until the excess ferrous ion is converted to the ferric state and the trivalent plutonium converted to the tetravalent state, then forming a bismuth phosphate precipitate in said solution and separating it therefrom together with the associated plutonium.

5. The method of separating dissolved hexavalent plutonium contained in an aqueous 0.5-1.5 N HNO₃ solution also containing a holding oxidant of Cr₂O₇²⁻ ion, which comprises treating said solution with an amount of ferrous ion in excess of that necessary to reduce substantially completely the dichromate ion present and to reduce the hexavalent plutonium present to the trivalent state, then digesting the solution at between 50 and 100°C. until the ferrous ion present is converted to the ferric state and the trivalent plutonium converted to the tetravalent state, then forming a bismuth phosphate precipitate in the solution and separating it, together with 25 associated tetravalent plutonium, therefrom.

6. The method of separating hexavalent plutonium from an aqueous solution containing 0.5-1.5 N HNO₃, approximately 0.6 M H₃PO₄ and approximately 0.1 M K₂Cr₂O₇, which comprises introducing ferrous ion in 30 sufficient quantity to give a ferrous concentration of between 0.0025 and .03 M after reduction of the dichromate ion present, digesting the solution at a temperature between 40 and 90° C. until the excess ferrous ion is oxidized and the trivalent plutonium is oxidized to the 35 tetravalent state, then forming a bismuth phosphate precipitate in the solution by introducing a soluble bismuth compound and a soluble phosphate compound in that order, and separating the bismuth phosphate precipitate thus formed together with associated plutonium from the 40 solution.

7. The method of separating hexavalent plutonium from an aqueous nitric acid solution containing hexavalent plutonium and dichromate ion, which comprises introducing 45 into the solution an amount of hydrogen peroxide sufficient to reduce substantially completely the dichromate ion present, then introducing ferrous ion in an amount sufficient to reduce the hexavalent plutonium ion present to the tetravalent state, then forming a tetravalent plutonium carrier precipitate in the solution and separating it therefrom.

8. The method of separating hexavalent plutonium from aqueous HNO₃ solution also containing dichromate ion and fluoride ion, which comprises introducing hydrogen peroxide sufficient to reduce substantially completely 55 the dichromate ion present and then introducing ferrous ion in excess of the theoretical amount necessary to reduce the hexavalent plutonium ion present to the tetravalent state, then forming a carrier precipitate for tetravalent plutonium in the solution and separating the precipitate therefrom.

9. The method of separating plutonium from an aqueous nitric acid solution containing hexavalent plutonium, dichromate ions and fluoride ions, which comprises introducing hydrogen peroxide in an amount sufficient to reduce substantially completely the dichromate ion present, then introducing ferrous ion in an amount between 22 and 33% equivalent to the dichromate ion originally present, then forming a lanthanum fluoride precipitate in the solution and separating it therefrom together with the associated plutonium.

10. A method of separating plutonium values from rare earth metal values contained in an aqueous nitric acid solution and containing the plutonium in the hexavalent state, comprising adding ferrous ions to said solution and heating said solution to 50 to 90° C. whereby 75

the plutonium is converted to and secured in the tetravalent state, thereafter adding bismuth cation and phosphate anions to said solution whereby bismuth phosphate and plutonium (IV) phosphate are precipitated while said rare earth metal values, primarily due to the solubilizing effect of iron ions, remain in solution.

11. A method of separating plutonium values from rare earth metal values contained in an aqueous nitric acid solution and containing the plutonium in the hexavalent state, comprising adding ferrous ions and fluoride anions to said solution whereby the plutonium is secured in the tetravalent state, thereafter adding bismuth cations and phosphate anions to said solution whereby bismuth phosphate and plutonium (IV) phosphate are precipi-

tated while said rare earth metal values, primarily due to the solubilizing effect of iron ions, remain in solution.
